(57) **CLAIM**

The ornamental design for an adapter for pipe joints, as shown and described.

DESCRIPTION

1. Adapter for pipe joints

1.1 : Perspective

1.2 : Front

1.3 : Back

1.4 : Left

1.5 : Right

1.6 : Top

1.7 : Bottom

The broken lines shown in the drawings illustrate portions of the adapter for pipe joints and form no part of the claimed design. The adapter for pipe joints is shown with a symbolic break in its length. The appearance of any portion of the article between the break lines forms no part of the claimed design.

1 Claim, 7 Drawing Sheets
